UNITED STATES PATENT OFFICE.

FRANK O. SWENSON, OF AUSTIN, TEXAS.

DOOR ATTACHMENT.

1,386,541.

Specification of Letters Patent.

Patented Aug. 2, 1921.

Application filed February 12, 1919. Serial No. 276,612.

To all whom it may concern:

Be it known that I, FRANK O. SWENSON, a citizen of the United States, residing at Austin, in the county of Travis and State 5 of Texas, have invented new and useful Improvements in Door Attachments, of which the following is a specification.

This invention relates to a weather strip attachment for doors, and has for its object 10 to provide means whereby the strip will be automatically brought in tight engagement with the carpet strip of the door frame, when the door is in closed position and which will further automatically move 15 away from the carpet strip upon the opening of the door, so as to provide no obstruction to the free opening or to the free closing of the door.

A further object of the invention is to 20 produce a weather strip which may be readily applied to any ordinary construction of swinging doors or the like, the construction of weatherstripping being of a simple nature, and the arrangement of the parts 25 thereof being such as to insure automatic action in projecting the strip below the door when the door is closed and in elevating the strip above the lower edge of the door when the door is open.

30 Other objects and advantages will present themselves as the nature of the invention is better understood, reference being had to the accompanying drawing, in which:

Figure 1 is an elevation of a door and 35 casing therefor, parts being broken away to illustrate the application of the improvement, the door being in its closed position.

Fig. 2 is an enlarged detail sectional view 40 approximately on the line 2—2 of Fig. 1.

Fig. 3 is a sectional view approximately on the line 3—3 of Fig. 2.

Fig. 4 is a view similar to Fig. 1, but illustrating the weather strip in retracted position, as when the door is open.

45 Fig. 5 is a sectional view approximately on the line 5—5 of Fig. 4.

Fig. 6 is a perspective view of the operating rod.

50 Fig. 7 is a similar view of one of the yokes employed.

Referring now to the drawings in detail, a swinging door is indicated by the numeral 10 and the casing for the door by the numeral 11, while 12 indicates the carpet strip.

55 The door has its lower edge plowed longitudinally providing the same with a con-

tinuous pocket 13, and the ends of this pocket may be closed by suitable plates 14, or if desired the pocket need not extend the entire width of the door, in which instance 60 the plates 14 may be dispensed with.

The top wall of the pocket, adjacent to the ends of the door is bored, to provide 65 sockets 15 and in these sockets are secured springs 16 that have their outer convolutions secured in eyes 17 that are centrally formed in substantially U-shaped yoke members 18. The limbs of the yokes have their ends also provided with eyes, the said limbs straddling the upper portion of a substantially cross sectionally rectangular weather strip 19, and securing elements 20 passing through the eyes and entering the said weather strip. By this arrangement the weather strip, which it should be stated 75 extends the entire length of the pocket 13 is drawn upwardly in the said pocket so that the outer edge thereof, which is preferably provided with a compressible facing, is elevated above the lower edge of the door. 80

Secured to the top wall of the pocket 13, adjacent to the ends of the said pocket are brackets 21 having openings therethrough which provide bearings for the longitudinally movable operating rod 22. The rod 85 22 projects through one end of the pocket 13, the said projecting portion being preferably provided with a flat head 23, and this end of the rod is normally projected through the said pocket by the influence of a spring 90 24 which is arranged on the rod and which exerts a pressure between one of the brackets 21 and a pin or lug 25 on the said rod. The rod is arranged above the strip 19 and is movable through the arm or limbs of the 95 yokes 17. The rod, adjacent to the ends thereof, has secured upon the lower face thereof angle elements which provide cam members and which are designated by the numerals 26. The upper edge of the strip 100 19 is provided with similar cam members 27, the outer beveled edges being at an opposite inclination from those of the cam members 26.

In the rabbet provided in the casing 11 105 in which the door 10 is hung, is secured a contact plate 28 disposed to be engaged by the head 23 of the rod 22 when the door is in its closed position. Such engagement forces the rod inward of the pocket, causing the 110 cam surfaces 26 thereof to travel over the cam surfaces 27 of the strip 19, and conse-

quently forces the strip downwardly and outwardly of the pocket 13 against the tension of the springs 16. When the door is swung to its open position the head 23 will 5 be free of contact with the plate 28, permitting the spring 24 to expand, moving the rod longitudinally to bring the cam elements thereon out of engagement with the cam elements on the strip and allowing the 10 springs 16 to draw the strip inward of the pocket.

It is, of course, obvious that the contact plate 28 may be dispensed with and that I am not to be limited to the details of the 15 construction above set forth, but am entitled to all such changes therefrom as fall within the scope of what is claimed.

Having thus described the invention, what is claimed as new, is:—

20 In combination with a hinged door provided with a pocket disposed longitudinally of its base and communicating with sockets

formed therein adjacent to its ends, a coil spring secured in each of said sockets, a depressible weather strip disposed in said pocket, U-shaped yoke members connected to said springs and secured to said strip, brackets secured to the inner wall of said pocket, a longitudinally movable operating rod carried by said brackets, provided with a flat head, and guided by said brackets and projecting through one end of said pocket, a lug extending from one side of said rod, a spring surrounding said rod and exerting a pressure between said lug and one of said brackets, cam elements formed on the upper edge of said strip, cam elements formed on the lower face of said rod and adapted to engage the first mentioned cam elements to force the weather strip outward against 40 the tension of the last mentioned spring.

In testimony whereof I affix my signature.

FRANK O. SWENSON.
